CHECK HOLDER

Roy B. French, Superior, W. Va.

Original application June 1, 1933, Serial No. 673,916. Divided and this application October 20, 1933, Serial No. 694,463

4 Claims. (Cl. 40—15)

The present invention relates to new and useful improvements in check holders for use on mine cars and is a division of my co-pending application Serial No. 673,916, filed June 1, 1933.

5 The primary object of the present invention is to provide, in a manner as hereinafter set forth, a check holder for mine cars embodying a novel construction, combination and arrangement of parts through the medium of which the 10 use of a sufficiently strong magnet is necessitated for releasing the check.

Other objects of the invention are to provide 15 a check holder of the aforementioned character which will be comparatively simple in construction, strong, durable, highly efficient and reliable in use, compact and which may be manufactured at low cost.

All of the foregoing and still further objects 20 and advantages of the invention will become apparent from a study of the following specification, taken in connection with the accompanying drawing wherein like characters of reference designate corresponding parts throughout the several views, and wherein:

25 Figure 1 is a view in front elevation of a check holder constructed in accordance with the present invention.

Figure 2 is a view in bottom plan thereof.

Figure 3 is a view in vertical section through 30 the check holder, taken substantially on the line 3—3 of Figure 1.

Figure 4 is a horizontal sectional view, taken substantially on the line 4—4 of Figure 1.

Figure 5 is a detail view in rear elevation of 35 an inner portion of the check holder.

Figure 6 is a detail view in front elevation of that portion of the holder shown in Figure 5.

Figure 7 is a view in front elevation of a 40 check.

Figure 8 is a view in side elevation of the check.

Referring now to the drawing in detail, it will be seen that the embodiment of the present invention which has been illustrated comprises a casing which is designated generally by the reference numeral 1, said casing including a back plate 2 having apertured ears 3 projecting therefrom which accommodate securing elements 4 for mounting the holder on a mine car, a portion of which is indicated at 5.

50 The casing 1 further includes a front plate 6 and intermediate plates 7 and 8 which are secured on the back plate 2 of said casing through the medium of screws 9. The plates 6 and 8 are formed to provide a chamber 10 which is

open at the bottom of the casing 1, said chamber 10 being divided into compartments by the plate 7.

On the lower portion of the plate 7 a transverse boss 11 is provided which, if desired, may be integral with the plate 7. Mounted on the boss 11 for operation in the outer compartment of the chamber 10 is a resilient latch 12 having mounted on its upper end portion a head 13 which is operable in an opening 14 provided therefor in the plate 7. The head 13 is beveled, as illustrated to advantage in Figure 3 of the drawing, and said head includes an integral, threaded shank 15 which extends through the resilient latch 12. Threadedly mounted on the shank 15 is an armature 16. The reference numeral 17 designates a spacing washer which is mounted between the armature 16 and the latch 12. It may be well to here mention that the casing 1 is of non-magnetic metal.

The inner compartment of the chamber 10 slidably receives a numbered check which is designated by the reference numeral 18. The check 18 is in the form of a substantially flat, metallic plate having a slot 19 in its upper portion for the reception of the head 13. The check 18 is further provided with an opening 20 in its lower portion, the purpose of which will be presently set forth. Projecting from the opposite faces of the check 18 are guards 21 which prevent the insertion of an instrument in the holder by unauthorized persons for disengaging the head 13 and thereby releasing the check. The opposed faces of the partition plate 7 and the plate 8 are provided with channels 22 which accommodate the guards 21. When the check 18 is in position in the casing 1, the opening 20 is aligned with notches or recesses 23 and 24 in the lower portions of the partition plate 7 and the front plate 6, respectively.

95 The beveled head 13 normally projects through the opening 14 in the partition plate 7 into the inner compartment of the chamber 10. As illustrated to advantage in Figure 4 of the drawing, the head 13 is formed to provide side shoulders which bear against the front face of the partition plate 7.

The check 18 is slid upwardly in the casing 1 between the partition plate 7 and the plate 8, the beveled head 13 being forced forwardly and then snapping into the slot 19 of the check. It will thus be seen that the check 18 is positively locked in the holder. To release the check, a suitable magnet is engaged with the front of the casing 1 for attracting the armature 16, thereby with- 105 110

- drawing the head 13 from the slot 19 for permitting the check to fall by gravity out of the holder. Should the check, for any reason, fail to drop by gravity out of the holder when the head 13 is disengaged from the slot 19, the removal of the 5 check may be conveniently accomplished by inserting a suitable instrument in the opening 20 through the notches or recesses 23 and 24 of the casing 1.
- 10 It is believed that the many advantages of a check holder constructed in accordance with the present invention will be readily understood, and although a preferred embodiment of the invention is as illustrated and described, it is to be understood 15 that changes in the details of construction and in the combination and arrangement of parts may be resorted to which will fall within the scope of the invention as claimed.
- What is claimed is:
- 20 1. A check holder comprising a casing having a chamber therein for the reception of a check and including a partition plate dividing the chamber into compartments, said plate having an opening therein, a resilient latch mounted on the plate and operable in one of the compartments, the other compartment being for the reception of the 25 check, a beveled head mounted on the resilient latch and operable through the opening for engagement with the check, and an armature mounted on the resilient latch and constituting magnetic force responsive means for actuating the latch for disengaging the head from the 30 check.

- 150
2. A check holder comprising a casing having a chamber therein and including a partition plate dividing the chamber into compartments, one of the compartments being for the reception of a check, the plate having an opening therein, a resilient latch mounted on the plate in the other compartment, a beveled head mounted on the resilient latch and operable in the opening for engagement with the check, said head including a threaded shank projecting through the latch, and an armature mounted on the shank and constituting magnetic force responsive means for actuating the latch for disengaging the head from the check.
3. In combination, a check, a check holder comprising a casing having a chamber therein for the reception of the check and including magnetic force responsive means for releasably securing the check in said casing, and guard means on the check for preventing the insertion of an object to release said force responsive means when the check is in locked position in the casing.
4. In combination, a check holder comprising a casing, a check removably mounted in the casing, magnetic force responsive means engageable with the check for releasably securing said check in the casing and guards on the check for preventing the insertion of an object to release said force responsive means when the check is in locked position in the casing.
